LOOP KNITTING DEVICE

Fermin P. Saldain, Buenos Aires, Argentina

Application May 19, 1944, Serial No. 536,279

4 Claims. (Cl. 66—117)

The present invention refers to a loop knitting device, particularly suitable for picking up run or fallen loops, being of the type which comprises a needle with its point or end of hook shape and a locking member hinged to said needle parallel to its normal axis, which in one of the end positions of the needle engages with the point of the needle, forming a loop between the needle and said locking member.

This type of needle is commonly used in the above mentioned work, and in said device, the locking member acts as a thread selector, being operated by the proper threads of the loop, in both the rising and the descending strokes of the needle.

Owing to this particular manner of operation, the said locking member will frequently act to push into the hook some of the threads which are thus added to the thread already held by the hook, so that it will be necessary to stop the work and proceed to separate the two threads.

The device forming the object of the present invention is essentially characterized by that the needle is mounted on means which perform the opening of the loop by causing the rotation or swinging of the locking member during the descending stroke of the needle and thus serve as a guide for said locking member during its rotation in the reverse direction, thereby preventing the same from engaging with the surface of the loop.

Another characteristic of the invention consists in that the said means for operating and guiding the locking member are maintained in contact with the same until the moment of closure of the loop, and will only separate therefrom after said closure, for allowing the passage of the loop thread which was supported on the back of the locking member, so that the said thread cannot escape from the locking member before the closure of the loop and thus allow said thread to enter into the loop.

A novel feature of the invention consists in the provision of a guide means for the needle which, while allowing a longitudinal advance of the same, prevents the rotation of the needle on its own axis.

Other details of the invention will be appreciated in the course of the following description of preferred embodiment of the same, illustrated by way of example in the accompanying drawing, in which:

Figure 1 shows a side view of the device, partially sectional.

Figure 2 is a similar view, but showing another position of the needle.

Figure 3 shows the device according to a section on the line A—A of Figure 1.

Figure 4 is a bottom view of the device.

In the different figures, the same numbers of reference have been used to indicate like or corresponding parts.

With reference to said drawing, the device consists of a column 1, from the lower part of which extends a slide 2, constituted by a plate forming an obtuse angle with said column 1 and provided with an opening 3 at the base of said column, and beyond the said opening 3, a recess 4 is formed 15 on the upper surface, and another recess 5 in the lower surface of said plate, so as to form a blade 6, inclined with regard to the plane of the slide 2.

On the column 1 are arranged, at different heights, projections 7, provided with rectangular holes, in which is placed a needle 8 of a corresponding section, which ends with a sphere 9 at its upper part and is provided at its lower end with a point 10, bent to form a hook and projecting toward the opposite side of the column 25 1. To the needle 8 is hinged at a point near the hook 10, a locking member 11, adapted to swing in the same plane on which is arranged the hook 10.

The slide 2 is provided with a plurality of orifices 12 for the purpose of reducing the weight of the device.

Supposing now the device to be in the position shown in Figure 1, the slide 2 bears with its lower face on the threads which are to form the loop, and the needle 8, in consequence, passes between two of said threads. The locking member 11 will closely apply its end against the needle 8, so that between the two parts a small notch will be formed, adapted to engage, at one time, with a single thread during the rising stroke of the needle 8, so as to draw said thread through the opening 3 of the slide 2. The said thread will exert a strong traction on the locking member 11 and thereby oblige the same to rest on the upper face of the small blade 6, while closing the same on the hook 10, which latter, when passing between the threads of the loop, will engage with one of the same and cause its passage through the opening 3. As soon as the hook 10 passes beyond the orifice 3, which it will do snugly applied against the plate 6, the locking member 11 will contact with said hook 10 and thus allow the thread which was held on the locking member 11, to pass to the lower part of the slide 2.

As the needle 8 descends, the end of the lock-

ing member 11 will come into contact with the small blade 6 and will be obliged to open and again occupy the position shown in Figure 1, so that the thread engaged in the hook 10 will be allowed to freely slip over said member. Meanwhile, the needle 8 will have descended behind the first of said threads and will thus have been interlocked by the second of the said threads, whereupon the device will return to its initial position, ready to repeat the operative cycle.

It should be noted that the foregoing description is given by way of illustrative example only, without limiting the invention, and that several modifications of form, construction and detail may be introduced within the scope of the invention, as clearly set forth in the following claims.

Having now particularly described and ascertained my said invention and in what manner the same is to be performed, I declare that what I claim and desire to secure by Letters Patent is:

1. Device for knitting loops comprising a needle having one end bent in the shape of a hook; a locking member turnably hinged to said needle and adapted to form an eye with said hook; opening means for opening said eye of said needle arranged above the threads of the loop and consisting of an inclined thin plate arranged with its upper edge facing the end of the locking member when it maintains said eye in its closed position, the said upper edge of said thin plate being arranged from the axis of said needle at the same distance as the outermost edge of said hook of said needle; and means for guiding said needle during its movement through said opening means.

2. Device for knitting loops comprising a needle having one end bent in the shape of a hook; a locking member turnably hinged to said needle and adapted to form an eye with said hook; opening means for opening said eye of said needle arranged above the threads of the loop and consisting of an inclined thin plate arranged with its upper edge facing the end of the locking member when it maintains said eye in its closed position, the said upper edge of said thin plate being arranged from the axis of said needle at the same distance as the outermost edge of said hook of

said needle; and means for guiding said needle during its movement through said opening means, said guiding means consisting of a column arranged parallel to said needle and firmly secured to said means for opening said eye of said needle, said column being provided with openings having a cross section being similar to that of said needle so as to enable guided movement of said needle through said openings.

3. Device for knitting loops comprising a needle having one end bent in the shape of a hook, a locking member turnably hinged to said needle near said hook and adapted to form an eye with said hook, means for guiding said needle arranged parallel to said needle, said guiding means being provided with several openings having a cross section being similar to that of said needle passing through said openings, means for opening said eye of said needle consisting of an inclined thin plate having an upper edge arranged adjacent to the end of said locking member and facing the same when said locking member maintains said eye in its closed position, said upper edge of said inclined thin plate being at the same distance from the longitudinal axis of said needle as that point of said hook which is farthest from said needle axis.

4. Device for knitting loops comprising a needle having a noncircular cross section and having one end bent in the shape of a hook, a locking member turnably hinged to said needle near said hook and adapted to form an eye with said hook, means for guiding said needle arranged parallel to said needle, said guiding means being provided with several openings having a cross section being similar to that of said needle passing through said openings, means for opening said eye of said needle consisting of an inclined thin plate having an upper edge arranged adjacent to the end of said locking member and facing the same when said locking member maintains said eye in its closed position, said upper edge of said inclined thin plate being at the same distance from the longitudinal axis of said needle as that point of said hook which is farthest from said needle axis.

FERMIN P. SALDAIN.
